UNITED STATES PATENT OFFICE.

EDWIN TAYLOR, OF BROOKLYN, NEW YORK, ASSIGNOR TO GERARD DEVELOPMENT COMPANY, A CORPORATION OF NEW YORK.

METHOD AND MEANS OF UTILIZING VOLATILE LIQUIDS AS A MOTIVE POWER.

939,757.

Specification of Letters Patent.

Patented Nov. 9, 1909.

Application filed March 16, 1906. Serial No. 306,459.

To all whom it may concern:

Be it known that I, EDWIN TAYLOR, a citizen of the United States, residing at Brooklyn, in the county of Kings and State of New York, have invented certain new and useful Improvements in Methods and Means of Utilizing Volatile Liquids as a Motive Power, of which the following is a specification.

10 Heretofore many attempts have been made to utilize for motor purposes the expansive action of the vapors of liquids more volatile than water, but great difficulty has been experienced, especially with large engines, 15 from inability to secure proper lubricating, resulting in cutting the cylinders and pistons and in friction and loss of power. This arises from the fact that most of the volatile liquids suitable for the purpose, such as bi- 20 sulfid of carbon, gasolene, ether, alcohol, etc., are non-lubricants and result in great frictional resistance.

I have discovered that the difficulties heretofore encountered in the use of expanding 25 vapors may be overcome and many advantages obtained by heating and operating together a mixture of relatively volatile and non-volatile liquids, preferably such as will together form a solution in all proportions, 30 one of said liquids being a lubricant and non-volatile at the pressures and temperatures employed, by which the engine or transformer of energy of any suitable character is fully lubricated, and this non-volatile 35 liquid is also capable of imparting its heat to the expanding vapor of the volatile liquid, thereby preventing condensation and maintaining its expansive efficiency, said vapor being thereafter condensed and the 40 liquid cooled and both returned to the boiler in solution. This method of utilizing the motor capacity of a volatile liquid may be employed in connection with transformers of different character and construction, and 45 for illustration, merely, I show in the accompanying drawing a rotary engine A, a boiler B with suitable heating means illustrated by a fire place C, a condenser D, pump E, and connecting pipes. There are two pipes 2, 3, 50 communicating one with the boiler at the top, and the other near the bottom, and both leading to the single supply pipe 4 of the engine. A valve device F constituting a

throttle is so constructed as to simultaneously control the flow through both pipes 2, 55 3 in proper relative proportions.

In general, I make use of a combination of a fixed mineral oil, giving off no vapor at the temperatures employed (up to 500° F.), and a suitable volatile liquid having a boiling-point and a latent heat of evaporation lower than that of water, said liquid being preferably a solvent in all proportions of said oil, and capable of being separated from said oil without decomposition by means of heat. This liquid must be capable of being repeatedly vaporized and condensed without decomposition and the consequent formation of a fixed gas which would require frequent blowing off of the condenser. Further, it 70 must exert practically no chemical action on the materials used in any part with which it may contact. Among such liquids are carbon-bisulfid, ether or gasolene, and of these I have found carbon-bisulfid to be most effective. The non-volatile liquid employed is preferably a pure mineral oil of high viscosity and fire-test: what is commonly known as "cylinder stock oil". The mixture is introduced into the boiler and heated until the desired pressure is attained, a portion of the volatile liquid being volatilized, the pressure maintaining the remainder in a liquid condition in the mixture, according to well known laws. The valve device controls the 80 flow of both the vapor and liquid, which then enter the single pipe 4 running to the transformer where the bisulfid vapor acts expansively to drive the motor, while the oil performs three functions, viz.—It lubricates 85 the engine. It serves to prevent leakages of vapor through small interstices between the running parts, and it affords super-heat to the vapor during expansion owing to its non-volatility and high initial heat which it must 90 give up to the vapor as the latter cools during expansion. From the transformer, both liquid and vapor pass through a common exhaust to the condenser, where the liquid again aids the process by combining with or 100 holding in solution the condensed vapor. From the condenser, the combination passes by means of the pump to the boiler, and the cycle is repeated indefinitely.

I wish it to be understood that I do not 105 limit myself to the employment of any par-

ticular liquids or combination thereof, nor to any special form of transformer, but

I claim—

1. The within described method of utilizing the energy of a volatile liquid, the same consisting in carrying together defined proportions of said liquid in a volatile state and a non-volatile liquid, both in a heated state, to a transformer of energy, wherein the expansive force of the volatilized liquid is utilized in the presence of the other in its liquid state.

2. The within described method of utilizing the energy of a plurality of liquids of different vaporizing points, the same consisting in heating the said combination until one is vaporized while another remains in liquid form, carrying both in defined proportions through a transformer and thereafter condensing the vaporized liquid in the presence of the non-vaporized liquid.

3. The within described method of utilizing the energy of a volatile liquid, the same consisting in mixing it with another liquid having a higher vaporizing point, heating the mixture to volatilize a portion of the volatile liquid, conducting the one in a gaseous and the other in a liquid state in different but regulated proportions to, and utilizing the expansive force of the gas in the presence of the non-volatile liquid in, a transformer, and thereafter condensing the gas in the presence of the liquid.

4. The within described method of utilizing the energy of a volatile liquid, the same consisting in mixing the liquid with a lubricating liquid having a higher vaporizing point, heating the mixture to vaporize a portion of the volatile liquid, and conducting the vapor so formed and the other liquid in

a liquid state in regulated quantities to a transformer of energy the proportions of the vapor and the liquid conducted to the transformer being independent of the proportions of the mixed liquids.

45

5. The combination with an engine for utilizing the expansive force of a volatile liquid, of means for volatilizing a part of a mixture of relatively volatile and non-volatile liquids, pipes for conducting both the gas and liquid as such to the engine, a single valve device constructed to control the combined flow of the gas and liquid in the required proportions to the engine, a condenser, and means for returning the mixture to the boiler.

6. The combination with an engine of a generator containing a mixture of a volatile and a non-volatile lubricating liquid, a pipe for conducting the volatile liquid as a vapor to the engine to drive the same, and a second pipe for conducting the non-volatile lubricating liquid as a liquid to the engine for lubricating the same.

7. The combination with an engine of a generator containing a mixture of a volatile and a non-volatile lubricating liquid, a pipe for conducting the volatile liquid as a vapor to the engine to operate the same, a second pipe for conducting the non-volatile lubricating liquid as a liquid to the engine to lubricate the same, and means to regulate the supply of the non-volatile lubricating liquid.

In testimony whereof I affix my signature in presence of two witnesses.

EDWIN TAYLOR.
